Inventor
Frank F. Burton
by Seymour Pearce, attorney

UNITED STATES PATENT OFFICE.

FRANK F. BURTON, OF MOUNT CARMEL, CONNECTICUT, ASSIGNOR TO WINCHESTER REPEATING ARMS CO., OF NEW HAVEN, CONNECTICUT, A CORPORATION.

BOLT-ACTION FIREARM.

Application filed November 28, 1925. Serial No. 71,896.

Fig. 1 is a broken view in right-hand side elevation of a bolt-action firearm embodying my invention, the parts being shown in the closed and locked position of the bolt.

5 Fig. 2 is a view thereof in transverse section on the line 2—2 of Fig. 1.

Fig. 3 is a corresponding view, showing the bolt as unlocked by the lifting of its handle.

10 Fig. 4 is a broken, plan view of my improved firearm, with the forward portion of the receiver shown in horizontal section.

Fig. 5 is a detached, plan view of the breech-bolt, shown as stripped.

15 Fig. 6 is an end view thereof.

My invention relates to an improved bolt-action firearm, the object being to produce a simple, reliable, rugged and easy-working arm constructed with particular reference to 20 preventing the bolt from cramping in either its forward and rearward excursions.

With these ends in view, my invention consists in a bolt-action firearm characterized by having its bolt formed with a guide-lug located between its ends and riding upon a bearing-shelf within the receiver of the arm, so as to prevent its being cramped in its forward or rearward excursions.

25 My invention further consists in a bolt-action firearm characterized as above set forth and having further details of construction as will be hereinafter described and pointed out in the claim.

In carrying out my invention, as herein shown, the reciprocating-bolt 10 is provided on its left-hand side, at about midway of its length, with an integral guide-lug 11 having a long bearing-face 12 which, when the bolt is turned through an angle of 90° 40 and, therefore, into its unlocked position, rides upon the horizontal face of a bearing-shelf 13, as shown in Fig. 3, the said shelf being formed integral with the receiver 14 (which may be of any approved construction in other respects) and projecting inwardly from the left-hand wall thereof and extending substantially the entire length thereof.

At its forward end, the bolt 10 is provided 50 with two integral, oppositely-located locking-lugs 15 and 16 entering, when the bolt is closed, an annular recess 17 formed in the forward end of the receiver and having a pair of locking-shoulders 18 and 19 with 55 which the rear faces of the said lugs 15 and

16 respectively co-operate to lock the bolt in its said closed position. The bottom face 20 of the locking-lug 15 is constructed to lie in the plane of the bearing-face 12 of the guide-lug 11, so that in the forward and rearward 60 excursions of the bolt, the said faces 12 and 20 ride simultaneously upon the bearing-shelf 13 aforesaid.

Under this construction, the bolt is effectively prevented from cramping, since it is 65 supported not only at its forward end by the locking-lug 15, but also midway of its length by the guide-lug 11, which, on account of its location about midway the length of the bolt, forms a completely effective guide 70 therefor. By preference, the guiding action of the guide-lug 11 and locking-lug 15 is supplemented by constructing the primary extraction-cam 21 integral with the rear end of the bolt, so that its end-face 22 also lies 75 in the plane of the faces 12 and 20, as shown in Fig. 5, whereby the bolt, in its forward and rearward excursions, is supported in a supplementary way by the end-face 22 of the extraction-cam. However, it is not imperative 80 that the face 22 just described shall lie in the plane of the faces 12 and 20, though I consider it a desirable construction.

At its rear end, the bolt is provided with an operating-handle 23, made integral therewith and offsetting to the right. To the rear of this handle, the bolt is provided with a pivotal safety lock 24 having an offsetting thumb-piece 25 also extending to the right.

As shown, the trigger-guard 26, receiver 90 14, and the stock 27 are bound together by means of three guard-screws 28, 29 and 30, which serve to insure the linear integrity of the organization.

I claim:

In a bolt-action firearm, the combination with a receiver, having a longitudinal guide-surface, of a reciprocating breech-bolt provided with a locking-lug at its front end, a cam-lug at its rear end, and a guide-member positioned between the said lugs; the said lugs and the said guide-member being adapted to co-operate with the said guide-surface of the said receiver, whereby the breech-bolt is prevented from cramping in the said receiver when being reciprocated therein.

In testimony whereof, I have signed this specification.

FRANK F. BURTON.
